Edward L. Morris

UNITED STATES PATENT OFFICE.

EDWARD L. MORRIS, OF BOSTON, MASSACHUSETTS.

DESIGN FOR A CLOCK-CASE.

SPECIFICATION forming part of Design No. 12,110, dated January 11, 1881.

Application filed December 17, 1880. Term of patent 14 years.

To all whom it may concern:

Be it known that I, EDWARD L. MORRIS, a citizen of the United States, residing at Boston, in the county of Suffolk and State of Massachusetts, have invented and produced a new and original Design for Clocks, of which the following is a specification; reference being had to the accompanying drawings, forming part thereof.

10 A represents a base or background arranged to contain the works of a clock.

15 B B represent a bicycle attached to or engraved upon the base or background. Upon the bicycle B is a figure, C, representing a rider of the bicycle. The large wheel of the bicycle has figures or marks about its rim corresponding to the marks indicating hours and minutes upon a clock dial or face, and the small wheel is marked to correspond to the 20 circle indicating seconds upon a clock-face. Shafts projecting through the background A connect the clock machinery with hands or

pointers which mark time upon the wheels of the bicycle B.

What I claim is—

1. A design for a clock, consisting of a base or background, A, arranged to contain clock-work, and faced with the representation of a bicycle, B.

2. A design for a clock, consisting of a base or background, A, arranged to contain clock-work, and faced with the representation of a bicycle, B, the wheels of which bicycle are caused to serve the purpose of a clock dial or face.

3. A design for a clock, consisting of a base or background, A, arranged to contain clock-work, and faced with the representation of a bicycle, B, the bicycle being surmounted by a rider, C.

EDWARD L. MORRIS.
